UNITED STATES PATENT OFFICE

144,344

DESIGN FOR AN ARMORED MOTORCYCLE

Seal True Alexander, Vista, Calif.

Application March 2, 1945, Serial No. 118,235

Term of patent 3½ years

(Cl. D90—8)

To all whom it may concern:

Be it known that I, Seal T. Alexander, a citizen of the United States, residing at Vista, in the county of San Diego and State of California, have invented a new, original, and ornamental Design for an Armored Motorcycle, of which the following is a specification, reference being had therein to the accompanying drawings, forming a part thereof, in which

I claim:

The ornamental design for an armored motorcycle, as shown.

SEAL TRUE ALEXANDER.
